(57) CLAIM

I claim the ornamental design for an avocado slicer, as shown and described.

DESCRIPTION

FIG. 1 is a perspective view of the avocado slicer;

FIG. 2 is a top view of the avocado slicer;

FIG. 3 is a bottom view of the avocado slicer;

FIG. 4 is a right side view of the avocado slicer, the left side view being the same as the right side view; and,

FIG. 5 is a front view of the avocado slicer, the back view being the same as the front view.
